CIRCUIT BREAKER

Samuel H. Boden and James M. Cumming, Turtle Creek, Pa., assignors to Westinghouse Electric Corporation, East Pittsburgh, Pa., a corporation of Pennsylvania

Application August 26, 1943, Serial No. 500,063

17 Claims.

(Cl. 200—82)

This invention relates to circuit breakers and more particularly to circuit breakers of the type which are operated by compressed gas motors.

The load curve of usual types of circuit breakers is such that maximum operating power is needed during the final portion of the closing movement when the contacts are being moved into high-pressure engagement. A solenoid is ideally suited for closing a circuit breaker since its power curve is very similar to the mechanical load curve of the circuit breaker developing maximum power near the end of its stroke. Compressed gas or air motors while being more desirable than a solenoid in other respects for closing a circuit breaker develop maximum power almost immediately at the beginning of the closing stroke. Because of this, excessive kinetic energy will be developed during the closing stroke and excessive slamming of the circuit breaker will result on normal closing operations unless some arrangement is made to take care of the difference in the power and load curves. On the other hand the application of full power is needed to quickly reverse and reclose the circuit breaker on quick reclosing operations.

An object of the present invention is the provision of a circuit breaker with an improved operating mechanism of the compressed gas operated type having means for preventing excessive acceleration during normal closing operations but which provides for the application of full power to the circuit breaker during the final portion of the closing stroke.

Another object of the invention is the provision of a circuit breaker with an improved operating mechanism of the compressed gas operated type having means for preventing excessive acceleration of the moving parts during normal closing operation but which provides for the application of full power to the circuit breaker during the final portion of the closing operation and also during quick reclosing operations.

Another object of the invention is to provide a circuit breaker with a device for equalizing the closing load on the operating mechanism.

Another object of the invention is to provide a circuit breaker wherein the closing load on the operating mechanism is increased for a predetermined portion of the closing stroke.

Another object of the invention is to provide a circuit breaker having means for applying an additional load on the operating mechanism and means for neutralizing the additional load at a predetermined time during a closing operation.

Another object of the invention is to provide

5 a circuit breaker with means interposed between the breaker and the operating mechanism for applying a force opposing closing movement of the breaker for a predetermined time during a closing operation.

10 Another object of the invention is to provide a circuit breaker having a load controlling device for providing a substantially even load on the operating mechanism throughout a closing operation thereof.

15 Another object of the invention is the provision of a circuit breaker having a compressed gas operating mechanism for closing the breaker with a device arranged to impose an additional load on the mechanism from the start of the closing stroke and release the additional load shortly prior to the time of contact engagement thus transferring the additional power used to move the superimposed load to the breaker at 20 this time.

25 Another object of the invention is the provision of a circuit breaker with an improved operating mechanism of the compressed gas operated type which is simple, reliable in operation, inexpensive to manufacture and which provides improved operating performance and efficiency.

30 The novel features that are considered characteristic of the invention are set forth in the appended claims. The invention itself, however, both as to structure and operation, together with 35 additional objects and advantages thereof will be best understood from the following detailed description of one embodiment thereof when read in connection with the accompanying drawing, 35 in which:

Figure 1 is an elevational view, partly in section and partly schematic, of a circuit breaker embodying the principles of the invention,

40 Fig. 2 is an elevational view of the load equalizing device shown in the closed position of the breaker.

45 Referring to the drawing, the circuit breaker indicated generally at 11, may be of any conventional construction either of the oil break, air break or gas blast type and is operated to the closed position by means of a compressed gas operated mechanism indicated generally at 13 on the drawing.

50 The operating mechanism includes a main casting 15 which is formed to provide a cylinder 17 closed at the upper end by an integral part of the casting. The lower end of the cylinder 17 is closed by means of a member 19 secured thereto and having a relatively large port 21 therein which is open to the atmosphere. An operating

lever 23 is pivotally mounted at one end on the casing 15 and consists of a pair of spaced parallel levers (only one being shown) connected at one end by means of a pivot pin 25 to the upper end of a pair of parallel links 27. The lower ends of the links 27 are pivoted by means of a pivot pin 29 on ears 31 (only one being shown) projecting from the main casting 15. The free ends of the operating levers 23 between them carry a short shaft 33 on which is mounted a latch roller 35 disposed between the levers 23.

The circuit breaker 11 is biased to open circuit position by means of an accelerating spring 37 and is connected to the operating mechanism 13 by means of a linkage comprising an operating rod 39 pivotally connected at its upper end by means of a pivot pin 41 to a bell crank 43. The bell crank 43 is rotatably mounted on a shaft 45 and is pivotally connected by means of a pivot pin 47 to a connecting rod 49 having its other end connected by means of a pivot pin 51 to a bell crank 53. The bell crank 53 is rotatably mounted on a shaft 55 supported on a fixed part and is connected by means of a pivot pin 57 to the breaker rod 59.

The breaker operating rod 39 is pivotally connected by a pivot pin 98 to the mid portion of the operating lever 23. In order to hold the breaker closed, following a closing operation thereof, the operating lever 23 is held in closed position by means of a latch mechanism indicated generally at 61. The latch mechanism comprises a main latch 63 pivotally supported on the main casting 15 by means of a pivot pin 65 and biased to latching position by a spring 67. The latch 63 is adapted to engage the latch roller 35 carried by the operating lever 23 to restrain the operating mechanism and the breaker in closed position. The latch face of the main latch 63 is so constructed that it will not, by itself, hold the operating lever 23 in closed position against the biasing influence of the accelerating spring 37. An auxiliary latch 69 is provided for engaging and holding the main latch 63 in latching position. The auxiliary latch 69 is pivotally mounted on the main casting 15 by means of a pivot pin 71 and is biased to latching position by means of a spring 73.

Means is provided to prevent engagement of the auxiliary latch 69 with the main latch 63 when the mechanism is in the open position and until the breaker is closed. This means consists of a lever 75 pivoted on the pin 71 and biased in a counterclockwise direction by means of a spring 77. The lever 75 has a projection 79 extending beneath a tail 81 of the auxiliary latch 69 and since the spring 71 is stronger than the spring 73, the lever 75 will hold the auxiliary latch 69 in unlatching position when the breaker is in the open position. Upon closing operation of the mechanism, the operating lever 23 engages the free end of the lever 75 and rotates it in a clockwise direction to permit the latch 69 to engage the main latch.

The latch mechanism 61 is adapted to be operated to release the operating lever 23 and permit opening of the breaker, by means of an electromagnetic trip device indicated generally at 83. This trip device comprises a core member 85 of magnetic material, an energizing coil 87, a movable armature 89 and a trip plunger 91. The trip plunger 91 is secured to the armature 89 and extends upwardly through a guide opening in the center portion of the core 85 and through an opening in a projection of the casing 15.

When the trip device 83 is energized, the armature 89 is moved upwardly causing the trip plunger 91 to engage the tail 81 of the auxiliary latch 69 and move the latch to unlatching position. The latch roller 35 then forces the main latch 63 to unlatching position which permits opening movement of the breaker mechanism.

The breaker is adapted to be closed by compressed gas admitted to the cylinder 17 above an operating piston 93. The piston 93 is secured to a piston rod 95 slidable through an air-tight opening in the top wall of the cylinder. A connector 97 is threadedly connected to the piston rod 95 and to the operating rod 39. The connector 97 is also pivotally connected to the operating lever 23 by means of the pivot pin 98 thus directly connecting the piston 93 to the breaker operating rod 39.

Compressed gas is admitted from an auxiliary reservoir 99 to the upper end of the cylinder 17 through an inlet passage 101 controlled by a main inlet valve 103 secured to the side of the casting 15. The opening operation of the main inlet valve 103 is, in turn, controlled by an electromagnetically operated pilot valve 105.

The pilot valve 105 is operated by an electromagnet 107 which, when energized, causes opening of the pilot valve 105 to admit compressed air from the tank 99 to operate the main inlet valve 103. Actuation of the inlet valve admits compressed gas to the upper end of the operating cylinder 17 which drives the piston 93 quickly downwardly to close the breaker.

When the mechanism is operated to closed position, the latch roller 35 engages the inclined surface of the main latch 63 and rotates the latch in a counterclockwise direction until the roller passes the nose of the latch. The spring 67 thereupon restores the main latch to latching position.

The mechanism cylinder is also provided with a dump valve (not shown) for quickly reducing or exhausting back pressure in the cylinder to permit high-speed opening of the circuit breaker. The dump valve is operated to open position by the pressure air in the cylinder when a pilot valve 108 is opened by the operation of the trip device 83. The fluid motor mechanism including the inlet and dump valve mechanisms is similar to that disclosed in the copending application of J. M. Cumming and R. C. Cunningham, Serial No. 410,686, filed September 13, 1941, and assigned to the assignee of the present invention. For details of construction of the fluid motor mechanism and its inlet and dump valve mechanisms reference may be had to the aforementioned copending application.

During a closing operation the greatest power of the operating mechanism is required to complete the closing stroke after the contacts touch to thereby provide the necessary contact pressure. It will be obvious that during the closing movement prior to the engagement of the contacts, the breaker mechanism moves relatively free and the full power of the closing mechanism has a tendency to cause slamming of the mechanism and circuit breaker. In order to prevent undesirable slamming and to provide a more even load curve for the mechanism, an additional or equalizing load is imposed upon the mechanism from the start of the closing stroke up until shortly before the engagement of the contacts, and the equalizing load is automatically removed at about the time the contacts touch or shortly before this time.

The load equalizing device comprises a loading coil spring 109 having the end coils of one end tightly coiled about a grooved spring anchor 111 which is pivotally supported on the pivot pin 41 connecting the operating rod 39 to the bell crank 43. The other end of the spring 109 is similarly attached to a spring anchor 113 pivotally connected by means of a pivot pin 115 to the free end of a lever 117 which is pivotally supported on a shaft 119. The shaft 45 supporting the bell crank 43 and the shaft 119 are mounted in the side walls 121 (only one being shown) of a housing which encloses the load equalizing device. The housing, including the sides 121, is secured in a suitable manner to the breaker frame or housing (not shown).

The spring anchors 111 and 113 are respectively provided with reduced portions 123 and 125 which extend toward and normally abut against each other, thus forming a solid but separable connection between the bell crank 43 and the lever 117. The lever 117 carries a pin 127 upon which is mounted an antifriction roller 129 adapted to cooperate with a cam 131 loosely mounted on the shaft 45 for rotary movement relative to the shaft and to the bell crank 43. Integral with the bell crank 43 is an arcuate projection 133 extending toward the cam 131 and adapted to cooperate with an arcuate projection 135 on the cam to form a lost motion connection between the cam 131 and the bell crank 43. The cam 131 is biased in clockwise direction about the shaft 45 by means of a spring 137 having one end hooked over a pin 139 on the cam and the other end anchored to an adjustable member 141 secured to the bottom of the housing 121.

Assuming the breaker to be in the open position, as shown in Fig. 1, when compressed gas is admitted to the top of the cylinder 17 above the piston 93, the piston is driven downwardly to close the breaker. This movement of the piston, through the piston rod 95 and the breaker operating rod 39 rotates the bell crank 43 in counterclockwise or closing direction. Since at this time the lower ends of the projections 133 and 135 are in engagement, the cam 131 will be rotated with the bell crank 43 and in the same direction. Counterclockwise rotation of the cam 131 permits the lever 117 to follow in a counterclockwise direction, but the configuration of the cam surface engaging the roller 129 is such that the lever 117 moves at a slower rate of speed than the bell crank 43; consequently the spring anchors 111 and 113 separate stretching the load spring 109 and the force of the spring 109 will be imposed upon the operating mechanism opposing closing movement thereof.

At a predetermined time during the closing movement, substantially when or shortly before the moving contacts engage the stationary contacts, the cam 131, in its counterclockwise movement, releases the roller 129 whereupon the spring 109 rotates the lever 117 sharply counterclockwise until the projecting ends 123 and 125 of the members 111 and 113 engage. Thereafter the lever 117 is free to move counterclockwise and the force of the spring 109 no longer opposes closing movement of the mechanism. This permits the full power of the closing mechanism 13 to be applied to the breaker during the latter part of the closing stroke.

When the cam 131 frees the roller 129 and the spring 109 rotates the lever 117 counterclockwise, the roller 129 moves the cam 131 in a counterclockwise direction relative to the bell crank 43,

thus partially closing the gap, indicated at 143, between the projections 133 and 135 and separating the projections at the point indicated at 145. As the closing movement continues, the projections 133 and 135 again engage at the point 145 and the parts assume the positions shown in Fig. 2 in the fully closed position of the mechanism.

When the breaker is in the fully closed and latched position and the trip device 83 is energized to trip the breaker in the previously described manner, the accelerating spring 37 actuates the movable contact and the operating mechanism to the open position (Fig. 1). During an opening operation, it is not desired that the force of the spring oppose the opening movement. During an opening operation the bell crank 43 is rotated in a clockwise direction from the Fig. 2 position to the open position (Fig. 1). The members 123 and 125 remain in contact during the entire opening movement and the solid connection formed thereby causes the lever 117 to rotate clockwise with the bell crank 43. During the closing movement, the spring 137 causes the cam 131 to rotate clockwise under the control of the roller 129 but since the spring 137 is much weaker than the spring 109, it cannot cause separation of the members 123 and 125. The projection 133 on the bell crank 43 will separate at the point 145 from the projection 135 on the cam 131 during the opening movement but the gap 143 will not completely close, and at no time during the opening movement is the cam 131 actuated by the bell crank. The bias of the spring 137 is applied during opening operations in a direction to aid the accelerating spring 37 in opening the breaker.

The circuit breaker is adapted for quick automatic reclosing operations which are preferably initiated immediately after the contacts are opened a predetermined distance and the arc is extinguished, and before the circuit breaker reaches full open position. The quick automatic reclosing operations of the breaker are initiated by admitting compressed gas to the operating cylinder at the proper time during the opening stroke. This is effected by the breaker control circuits which are fully described and shown in the previously mentioned copending application.

During such high-speed reclosing operations it is essential that the operating mechanism be relieved of the additional load imposed thereon by the spring 109 as full power is needed to quickly reverse the movement of the breaker and effect quick reclosing thereof. Referring to Fig. 2 which shows the load equalizing device in the fully closed position of the breaker, it will be remembered that the clockwise rotation of the bell crank 43 in opening direction through the now solid link 123-125 rotates the lever 117 also in a clockwise direction. During this action the cam 131 is prevented from immediately resuming its Fig. 1 position by engagement thereof with the roller 129, the bell crank moving clockwise relative to the cam 131 due to the lost motion connection 133-135. The contacts separate and the arc is extinguished just before the roller 129 releases the cam 131 and at this time compressed gas is admitted to the cylinder quickly driving the piston toward the bottom of the cylinder to thereby effect quick reclosing of the contacts. The counterclockwise movement of the bell crank 43 draws the roller 129 back under the cam 131 without causing separation of the members 123 and 125 and therefore does not apply the spring

load 109 to the mechanism during the quick reclosing operation.

From the foregoing description, it will be seen that there is provided a load equalizing device of simple construction, reliable in operation which applies an auxiliary load to the closing mechanism of a circuit breaker during a portion of the closing movement and which at a predetermined time during the closing movement automatically removes the auxiliary load to permit the full power of the closing mechanism to be applied to close the breaker contacts.

Having described the invention in accordance with the patent statutes, it is to be understood that various changes and modifications may be made in the structural details thereof without departing from some of the essential features of the invention.

We claim as our invention:

1. A circuit breaker comprising relatively movable contacts, operating mechanism for moving said contacts to closed position, spring means having one end attached to said operating mechanism for at times applying a force opposing closing movement of said breaker during a major part of the closing stroke, and means related to the other end of said spring operable by said operating mechanism near the end of a closing movement to render said spring means ineffective to oppose opening movement.

2. A circuit breaker comprising relatively movable contacts, operating mechanism operable to close said contacts, a spring having one end attached to said mechanism and normally disposed to oppose closing movement of said breaker at least during a portion of the closing movement, and means attached to the other end of said spring operable by said operating mechanism near the end of the closing movement to render said spring ineffective, said spring being ineffective to oppose opening movement of said breaker.

3. In a circuit breaker, power operating mechanism for closing said breaker, a spring having one end attached to said operating mechanism for opposing closing movement of said breaker, said spring being normally ineffective, means automatically operable during an opening operation to cause said spring to oppose closing movement of the breaker, said means being operable at a predetermined time during the closing movement to neutralize the force of said spring.

4. A circuit breaker comprising relatively movable contacts, power operated means for closing said contacts, a spring having one end attached to said power operated means, a member attached to the other end of said spring, means automatically operable during a closing operation to first restrain said member to thereby cause the spring to oppose the closing movement and then near the end of the closing movement to release said member and render said spring ineffective to oppose the final portion of said closing movement, and said spring being at all times ineffective to oppose opening movement.

5. A circuit breaker comprising relatively movable contacts, a fluid motor operable to close said contacts, a rotatable member operable by said motor to close the contacts, a spring having one end attached to said rotatable member, and a cam member automatically operable during an opening movement to cause said spring to apply a force opposing closing movement of the motor during a substantial portion of the closing movement of said motor.

6. A circuit breaker comprising relatively mov-

able contacts, a fluid motor operable to close said contacts, a source of fluid under pressure, means for admitting fluid under pressure to said motor to cause the motor to operate the breaker to closed position, means connected to said motor for applying an additional load to said motor during the closing operation, and means operable by said motor to reduce said additional load near the end of the closing operation.

10 7. A circuit breaker comprising relatively movable contacts, operating mechanism for said contacts comprising a cylinder, a piston movable in said cylinder, a source of compressed gas, means for admitting compressed gas to said cylinder to cause the piston to operate the breaker to closed position, spring means having one end attached to said operating mechanism for applying an additional load to said piston during the major portion of the closing stroke, and means comprising an element attached to the other end of said spring and operable to reduce the additional load at a predetermined time near the end of the closing stroke.

15 8. A circuit breaker comprising relatively movable contacts, operating mechanisms for said contacts comprising a cylinder, a piston movable in said cylinder, a source of compressed gas, means for admitting compressed gas to said cylinder for operating said piston to close said contacts, a spring having one end attached to a part movable with said piston for at times applying a force opposing closing movement of said piston, and means comprising a member connected to the other end of said spring and operable by 30 said part near the end of a closing operation to reduce the force of said spring.

9. In a circuit breaker, a fluid motor operable to close the breaker, resilient means connected to a part movable with the breaker for at times 40 applying a force opposing closing operation of the breaker, a cam rendered effective by movement of the breaker to open position to cause said resilient means to oppose a closing operation during a substantial portion of the closing operation, and means for operating said cam to reduce the force of said resilient means.

10. In a circuit breaker, power operated operating mechanism for closing said breaker, a load equalizing device comprising means for applying a force to said operating mechanism during a major part of the closing movement for retarding the closing movement of the breaker, and means automatically operable during the latter part of the closing operation and before the 55 breaker reaches fully closed position to reduce the retarding force.

11. A circuit breaker having relatively movable contacts, a motor operatively related to the movable contact for closing the circuit breaker, a spring having one end attached to a part movable with said motor, means automatically effective to cause said spring to impose an additional load on the motor during a substantial part of the circuit breaker closing stroke of said motor and to release 60 said additional load from the motor before the circuit breaker reaches the fully closed position on normal closing operations of the circuit breaker.

12. A circuit breaker having relatively movable contacts, a fluid motor operatively related to the movable contact for closing the circuit breaker, means automatically effective to apply an additional load on the fluid motor during a substantial part of the circuit breaker closing stroke of motor and to release said additional load from the 70 motor before the circuit breaker reaches the fully

closed position on normal closing operations of the circuit breaker, and an element controlled by said motor to render said means ineffective to apply said additional load on said motor during quick reclosing operations of the circuit breaker initiated before the circuit breaker reaches full open position.

13. A circuit breaker having relatively movable contacts, a fluid motor operatively related to the movable contact for closing the circuit breaker, means automatically effective to apply an additional load on the fluid motor during a part of the circuit breaker closing stroke of said motor and to release said additional load from the motor during the latter part of the closing stroke and before the circuit breaker reaches the fully closed position on normal closing operations of the circuit breaker, and means for preventing application of said additional load on said motor during quick reclosing operations of the circuit breaker.

14. A circuit breaker having relatively movable contacts, a fluid motor operatively related to the movable contact for closing the circuit breaker, spring means automatically effective to apply an additional load on said fluid motor during a substantial part of the closing stroke of the motor, means operable during a closing stroke of the motor to release said additional load, and means for controlling said spring means to prevent application of said additional load on said motor during quick reclosing operations of the circuit breaker.

15. A circuit breaker having relatively movable contacts, a fluid motor operatively related to the movable contact for closing said breaker, means comprising a spring automatically effective to apply an additional load on said fluid motor during a part of the closing stroke of said motor, a

cam operable during the latter part of the closing stroke of the motor to release said additional load, and means controlling said cam to prevent application of said additional load on said motor during quick reclosing operations of the circuit breaker.

16. A circuit breaker having relatively movable contacts, a fluid motor operatively related to the movable contact for closing the circuit breaker, 10 means comprising a spring connected to a part movable with said motor for imposing an additional load on said fluid motor during a substantial part of the closing stroke of said motor, a cam for controlling said spring and operable during a 15 normal closing operation of the breaker to release said additional load, and means for controlling said cam to prevent application of said additional load on said motor during quick reclosing operations of the breaker.
- 20 17. In a circuit breaker, operating mechanism for closing said breaker comprising a cylinder, a piston movable in said cylinder, a source of gas under pressure, means operable to admit gas under pressure to said cylinder to cause a closing 25 operation of said piston, a load equalizing device comprising means for applying an additional load to said operating mechanism during a substantial portion of the closing operation, means operable near the end of the closing operation and before 30 the breaker reaches fully closed position to automatically release the additional load, and means for controlling said load equalizing device to prevent application of the additional load to said operating mechanism during quick reclosing operations of the breaker initiated before the 35 breaker reaches full open position.
